UNITED STATES PATENT OFFICE.

LOUIS R. HORTON, OF PROVIDENCE, RHODE ISLAND, ASSIGNOR TO THE
J. B. & S. M. KNOWLES COMPANY, OF SAME PLACE.

DESIGN FOR A SPOON.

SPECIFICATION forming part of Design No. 25,193, dated February 25, 1896.

Application filed October 9, 1895. Serial No. 565,193. Term of patent 7 years.

To all whom it may concern:

Be it known that I, LOUIS R. HORTON, a citizen of the United States, residing at Providence, in the county of Providence and State 5 of Rhode Island, have invented and produced a new and original Design for a Spoon, of which the following is a specification, reference being had to the accompanying drawing, forming part thereof.

10 The drawing represents a spoon, illustrating my new design, attached to a conventional handle.

15 The leading feature of my design consists in a spoon having the bowl portion thereof or- namented, as hereinafter described.

In the drawing, 5 indicates the bowl, and 6 a handle of conventional shape attached to the bowl. The outline of the bowl resembles a shell. The portion of the bowl adjoining 20 the handle has on its inner edge a concave practically semicircular outline, and the front portion of the bowl opposite the handle has a succession of concaved scalloped outlines, giving to the whole bowl a practically oval out-

line. The plain concaved line extends on 25 each side from the handle to the points 7 7, and this portion is ornamented with the graduated bead-border 8. The larger beads, near the handle, being gradually reduced in size, terminate at points 7 7. The inward-curved scalloped 30 edges 9 9 form the margins of the concaved shell-panels 10 10, which panels diminishing in width and depth extend toward and merge with the concave plane rear portion of the bowl. The shell-like appearance of the bowl 35 is accentuated by the points formed between the concaved marginal lines 9 9 and the graduated beadings 8 8.

What I claim is—

The design for a spoon as herein shown and 40 described.

In witness whereof I have hereunto set my hand.

LOUIS R. HORTON.

Witnesses:

JOSEPH A. MILLER,
HENRY J. MILLER.
